UNITED STATES PATENT OFFICE.

ELMER C. PITCHER, OF SAN FRANCISCO, CALIFORNIA.

DISAPPEARING BED.

1,236,348.

Specification of Letters Patent. Patented Aug. 7, 1917.

Application filed April 20, 1914. Serial No. 833,234.

To all whom it may concern:

Be it known that I, ELMER C. PITCHER, a citizen of the United States, residing in the city and county of San Francisco, State 5 of California, (whose post-office address is Fifth & Bryant Sts.,) have invented a new and useful Improvement in Disappearing Beds, of which the following is a specification.

10 This invention relates more particularly to pivoted beds, adapted to swing into and out of closets, through an opening in the wall narrower than the width of the bed.

Among the objects of this invention are: 15 To provide a pivotal hanger for folding beds whereby they may be swung into and out of closets independent of the door, and have a movement tangential to the arc of the swing movement;

20 To so support the bed in its evolution that it may swing into a shallow closet, through a narrow door opening and leave a free passage through the opening, when the bed is in the operative and inoperative positions, independent of the door, so that the 25 door may be closed and locked when the bed is in either position.

Other objects and advantages will appear as the description progresses. I shall outline in full that form of the invention selected for illustration in the drawings accompanying and forming part of the present specification. The novelty of the invention will be included in the claims succeeding 35 said description. From this it will be apparent that I do not restrict myself to the showing made by said drawing and description, as I may adopt many variations, within the scope of my invention as expressed 40 in said claims.

In the drawings:

Figure 1— is a front elevation of a rotating door jamb having supporting brackets fixed thereto, supporting a folding bed in 45 accordance with this invention.

Fig. 2— is a plan view from above of the same; partially in cross section on the line 11—11.

In detail the construction illustrated in 50 the drawings includes, the rotating jamb 1, fixed to the vertical shaft 2, pivoted at 3 and 4 in the floor and the top of the door frame respectively. The rotary jamb is provided with the stops 5 and 6, engaging 55 the door X in the usual manner. The adjacent side of the door frame is provided

with the stile 7, with a concave face 8, struck from the pivotal center of the rotary jamb.

The top and bottom supporting brackets 9 and 10, are fixed to the jamb by the screws 60 11—tapped into the shaft. These brackets may be attached in various other ways; and the rotary jamb constructed in a manner most suitable for the purpose intended. For economy in construction the brackets 9 and 65 10, are alike each being provided with the rollers 12—12, upon which the top and bottom rails 13 and 14 of the head of the bed are adapted to travel. Owing to the limitations of the drawing paper in Figs. 1 and 2, 70 the width of the bed is shown as overhanging the door opening. It is obvious however, that by rolling the bed laterally, the full door opening is available, permitting the closing and locking of the door whenever the bed is entirely within or outside of 75 the closet.

For convenience in handling, the head of the bed is provided with supporting rollers 80 15 and 16 to support the overhanging portion of the bedstead, when it is moved laterally on the hangers. These rollers are preferably slightly above the plane of the floor, to avoid dragging on the carpet during the evolutions of the bed. The rollers 15 and 85 16 are casters and are adapted to support the overhanging weight, if the bed is moved in the let-down or operative position, or if it is moved without being centered on the hangers. Practice has proven that the extra 90 weight of the occupants in the bed will cause these rollers to bear on the floor without unduly straining any of the associated mechanisms.

For greater lucidity in the drawings the 95 invention is disclosed in its simplest form. Obviously beds constructed in accordance with this invention could be modified to completely conceal or disguise the presence of the various supporting fixtures as the occasion may require.

The bed operates substantially as follows:

The bedstead folded up as in Fig. 1, is rolled on the hangers until the weight centers thereon. This lifts the rollers 15 and 105 16 clear of the carpet, throwing the weight onto the chafing plate 17, at the bottom of the rotary jamb. In this position the bed is swung into the closet on the shaft 2, that is the axis of the swinging movement. The 110 lateral travel of the bedstead on the roller hangers is tangential to the arc of the swing

about the axis 2. This tangential movement makes it possible to maneuver the bed in swinging it through a narrow opening, into a shallow closet until it assumes the position illustrated in dotted lines in Fig. 2, in which position the hangers are on the opposite side of the center from the operative position, in which position they necessarily overhang the door opening within the closet, not a material objection. The reversal of the rotary jamb now presents the stops 6 to the edge of the door, into which it may be locked as described in connection with the stops 5. The rotary jamb can be trimmed to harmonize with the adjacent door trim making it a scarcely noticeable modification of the conventional door.

The folding bed has not been specifically described, inasmuch as many types of folding bedsteads are available for use in connection with this particular pivotal means. They all combine what will be called for convenience, the "head of the bed" to which the mattress frame is hinged on a horizontal pivot, the foot of the mattress being supported in the horizontal position by pivotal legs that swing down to support the mattress when it is lowered to a horizontal position. The bedstead in a vertical position is swung in and out of the receptacle through the opening, and may be lowered on its horizontal pivot for use within the room.

Having thus described this invention, what I claim and desire to secure by Letters Patent is;

1. In combination with a door opening; a rotary jamb; a door hinged in said opening engaging said jamb; and a bed attached to said jamb.
2. In combination with a door frame, a rotary jamb vertically pivoted adjacent to one side of the frame opening; a hanger attached to said jamb, and a bed engaging said hanger and having a movement tangential to the arc of the swing of said jamb.

3. The combination with a wall having an opening therein, of a vertically disposed shaft rotatably mounted in said opening, a door jamb attached to said shaft, a bed, and means attached to said jamb for slidably supporting said bed.

4. In combination with a door opening, a rotary jamb vertically pivoted in said opening, a concave stile adjacent to said jamb, door stops on opposite edges of said jamb; a door in said opening adapted to engage said stops and a bed attached to said jamb.

5. In combination with a door frame; a door mounted in said frame, a rotary jamb vertically pivoted in said frame; a hanger attached to said jamb; and a bed slidable on said hanger substantially parallel with the plane of said jamb, said jamb having inner and outer stops to coöperate with the door.

6. In combination with a door opening; a rotary jamb vertically pivoted in said opening; a door in said opening adapted to engage said jamb; a horizontal hanger spaced outward from said jamb; and a folding bed slidable on said hanger.

7. In combination with a door opening, a vertical shaft journaled in one side of said opening, a jamb on the shaft, upper and lower supports carried by and projecting outwardly from the jamb, and a bed mounted on the supports for horizontal movements thereof.

8. The combination with a wall having a door opening, of a rotatable jamb mounted at one side of said opening to swing on the arc of a circle, a bed carried by said jamb and having a sliding movement thereon within the closet toward or from the opposite side of said opening.

In testimony whereof I have hereunto set my hand this eleventh day of April, 1914.

ELMER C. PITCHER.
